UNITED STATES PATENT OFFICE.

HENNING G. SAHLIN, OF ROME, NEW YORK, ASSIGNOR TO GEORGE W. TURNER, OF ROME, NEW YORK.

MACHINE FOR WINDING EDGEWISE AND SPACING METAL STRIPS.

1,151,721.

Specification of Letters Patent.

Patented Aug. 31, 1915.

Application filed October 16, 1911. Serial No. 654,846.

To all whom it may concern:

Be it known that I, HENNING G. SAHLIN, of Rome, in the county of Oneida and State of New York, a citizen of the United States, 5 have invented new and useful Improvements in Machines for Winding Edgewise and Spacing Metal Strips, of which the following is a specification.

My invention relates to machines for 10 winding metal strips or ribbon edgewise and spacing the ribbons during the winding operation along the length of a cylinder. When the cylinder is a tube, such a product is useful in the construction of radiators for 15 automobiles where a large cooling surface is required in a small compass and where therefore regularity of spacing is very desirable to use the space most economically.

In my specification I have for convenience 20 referred to the cylinder as a tube and it is so shown in the drawings.

The preferred form of my invention is shown in the drawings, in which—

Figure 1 is a side view of a machine embodying my invention, Fig. 2 being a rear view. Fig. 3 is a section of the ribbon-forming head, Fig. 4 being a front view of the winding form and its holder, and Fig. 5 a top view thereof. Fig. 6 is a front view 30 of the winding head. Fig. 7 is a face view of the spreader. Fig. 8 is a section on line 8—8 of Fig. 7. Fig. 9 is a sectional view of the tube coupler in action. Fig. 10 is an elevation of the tube coupler in action and Fig. 35 11 is a section on line 11—11 of Fig. 10.

A, A¹ are uprights partly shown and suitably supported and forming with the yoke piece A² (shown only in part) bearings and supports for the various parts.

40 B is the metal tube or core on which is wound the metallic ribbon C by which the radiating surface of the tube is increased. The tube is held from rotating, but is fed forward progressively at an even speed by 45 means described below. The tube or core B passes through the center of the rotatable sleeve D. The sleeve D carries at its forward end an enlargement d which is recessed to receive a boss E extending rearward from the detachable disk E¹. The reel on which the metal ribbon is wound is lettered F and is mounted to turn on and independently of the enlargement d and between the disk E¹ and a disk G which carries a rearwardly-projecting hub G¹ at

tached to the enlargement d by the screw g. The screw g passing through the hub G¹ into a recess on the boss E also secures the detachable disk E¹ to the sleeve D while the machine is in operation. The disk E¹ must 60 be taken off when a new supply of ribbon is to be put onto the reel F. The disks E¹ and G thus rotate with the sleeve D and between them is the roll of the metallic ribbon C wound on the reel F which is free to turn 65 independently of the disks and sleeve as the ribbon is drawn off. On the face of the disk E¹ is a guide roll E² set on a stud at an angle to the face of the disk as shown and over which the ribbon is led to the holder H 70 which is also mounted on the face of the disk E¹. The ribbon is thus given a partial turn on the way to the tube B on which it is to be wound edgewise.

H¹ is a winding form threaded on its periphery to screw into the threaded interior of the holder H. The holder H is provided with a guideway h leading to the winding form H¹ and having a cover h¹ to cover the guideway. The winding form H¹ has a central opening which registers with the opening in the sleeve D and is just large enough to allow the tube B to pass through it and be centered therein.

The winding form H¹ is preferably machined from a steel cylinder. A spiral passage h² forms it into a continuous spiral strip which may be of any desired pitch according to the pitch at which the ribbon is to be wound on the tube. The thread in the 85 holder is cut to correspond so that the form will screw into the holder, a separate holder being used for each form. This passage serves as a die for the ribbon to lead it spirally to the tube and also to hold it in place 90 while the form is turned so that said ribbon will be properly spaced upon the tube, and for this purpose the form preferably has a number of turns communicating with the central opening in the die which receives 95 the tube or core, so that the ribbon shall not emerge from the form until it has firmly adjusted itself in place and also so that said form may be adjusted as below described 100 when it has begun to wear.

105 The die by which the bending of the ribbon is accomplished comprises the following parts:—In the guideway h is a guidestrip h³ which is curved at its lower end as at h⁴ to conform to the curvature of the form H¹, 110

The guidestrip is about 1/64 of an inch thicker than the thickness of the ribbon and forms one side of the guideway, its edge against which the ribbon bears being slightly 5 grooved to aid in its function as a guide. It is sufficiently long to lie within the spiral passage in the form and hold the ribbon against the tube, preventing its reaction. The guideway in the holder is at a slight 10 angle to the axis of the tube so as to lead the ribbon to the passage in the form in a plane parallel to the side of the said passage. The plane of the ribbon is thus turned by the roll E² and the guideway approximately 90° in 15 its delivery to the form.

The spiral is cut to any desired pitch and the sides of the passage are not flat, but are so cut that the inner portion of the passage bordering on the central opening for a width 20 equal to the width of the ribbon is equal to the width of the ribbon, while the receiving outer portion of the passage is about 1/64 of an inch wider to enable it to receive the end of the guidestrip h³ which sets into it to hold 25 the ribbon against the tube as above referred to. Thus the ribbon at the point where it enters the winding form is closely confined between four walls of which the tube is one, and held firmly while it takes its said shape 30 so that there is no tendency to wrinkling or crumpling.

I prefer to make the winding form somewhat longer than would otherwise be necessary in order that as it wears it may be 35 screwed into or out from the holder to present new surfaces to the ribbon. I prefer to make the holder as shown in the form of a strap, the ends h⁵ and h⁶ of which are clamped together by the screw h⁷. A screw 40 h⁸ attaches the holder to the face of the disk E¹.

In the machine shown the sleeve D is mounted in uprights A, A¹ and is rotated in the following manner: On the sleeve D is 45 mounted a friction disk J provided with a hub j and is free to turn on the sleeve. On its opposite side the disk J has a recessed hub j¹ having a face cam j². A hollow hub j³ is keyed to the sleeve D to slide thereon and 50 turn therewith, and between the hub j³ and the bearing in upright A are ball bearings j⁴ suitably mounted to reduce friction. The hub j³ also has a face cam like that on hub j², these cams taking up automatically the wear 55 of the friction rolls k and k¹ below described. A spring j⁵ in the chamber in hubs j¹, j³ tends to throw the disk J against the friction roll k.

J¹ is a second friction disk which is 60 mounted on a shaft J² preferably in the same way as disk J is mounted on the sleeve D, carried in the uprights A, A¹, and to which power may be applied in any suitable way, for example, by an electric motor either attached directly thereto or belted thereto as 65

seems best. A vertical shaft K has keyed to each end a friction roll, one of which k engages the disk J and the other k¹ the disk J¹. The shaft K is mounted in a sleeve k² which slides in a bearing K¹ bolted to the upright 70 A¹ and by means of it power is transmitted from disk J¹ to disk J. The relative speed of these disks is regulated by means of a rack k³ on the sleeve k² with which a segment k⁴ engages, this segment being mounted on the 75 upright A¹ and operated by the handle K² so that the sleeve k² may be raised or lowered and so move the friction rolls k, k¹ and their shaft along radii of the friction disks. The friction disk J¹ has a recess J³ near its 80 center so that by moving the bearing K¹ sufficiently far downward the friction roll k¹ will be moved toward the center of the disk J¹ and opposite the recess and out of contact with the disk so that it will not be moved by 85 the disk.

An important advantage of this friction drive lies in the fact that by moving the lever or handle K² the friction rolls k, k¹ are simultaneously moved along the surface of the 90 disks J, J¹ so that the speed of rotation of the driven portion of the machine may be very readily and simply adjusted with great accuracy and the machine itself may be almost instantly stopped by so moving the 95 parts that the roll k¹ will be opposite to the recess J³ in the disk J¹ so that the rotation of the disk J¹ will not affect the friction roll k¹ and hence no power will be conveyed to the disk J. 100

The sleeve D carries at its rear end a gear L which meshes with an intermediate gear L¹ in mesh with a gear L² mounted on a stud L³ secured to upright A¹ and supported by bracket R. The gear L² has an elongated 105 hub on which is cut a worm l so that the rotation of gear L² by gears L and L¹ causes the rotation of this worm. Two worm gears M and N, mounted on shafts m and n carried in bearings in brackets M¹, N¹ mounted free on stud L³, engage the worm l and are rotated by it. Each shaft m, n has at its upper end a grooved friction roll m¹ and n¹ which engages and feeds the tube B. A grooved idler roll m² supports the tube from 110 below. It is mounted on a stud m³ which is supported in the brackets M¹, N¹. 115

The brackets M¹, N¹ are held in place at their upper ends by the pressure lever Q. This lever is pivotally mounted on bracket 120 M¹. It has an opening q through which the tube B passes and a slot-shaped extension q¹ of said opening receives a screw q² which screws onto the bracket N¹ thus loosely connecting the lever and bracket. A weight Q¹ 125 on the lever Q tends to hold the upper ends of the brackets M¹ and N¹ together and thus the friction rolls m¹, n¹ are held against the tube B by a pressure which can be adjusted by moving the weight Q¹. 130

The stud L^3 carrying the gear L^2 carries a lever P free thereon upon which lever P the stud l^1 for the intermediate gear L^1 is mounted. P^1 is an arm projecting from the 5 upright A^1 and carrying a set screw p at its outer end on which runs the slot p^2 in the lever P . The gear L on sleeve D is a change gear and when a different pitch is needed for the winding operation another gear is substituted for it, the screw p being first 10 loosened so that the intermediate gear may be disengaged from it. After the new gear L is put in place the lever P is moved to remesh the intermediate gear L^1 with new gear L and gear L^2 and the screw p is again tightened.

When a considerable portion of the winding form extends from the holder so that there is chance for a good deal of friction to 20 be developed between the wound ribbon and the walls of the spiral passage i usually use a spreader R^1 which is screwed into the passage so shown in Figs. 1 and 3. This spreader in its preferred form is shown in 25 Figs. 7 and 8 and comprises an inclosing portion r which is nearly circular and is provided with a handle r^1 . The portion r has a greater external diameter than the form and an opening through it larger in diameter 30 than the diameter of the tube and ribbon combined but less than the diameter of the winding form. It is preferably thinned somewhat at its inner edge as at r^2 so that it will take in the spiral passage of the winding form, but it is left thick enough to 35 spread the passage somewhat. The outer edge r^3 of the thinned portion is of about the diameter of the winding form so that as the spreader is screwed into place this edge will 40 rest on the periphery of the winding form and so keep the spreader properly centered. The spreader is preferably made malleable to adjust itself to the pitch of the winding form.

45 It is very desirable that means shall be provided for coupling the ends of two tubes so that the winding operation will be continuous notwithstanding the fact that short lengths of tube are being wound. For this 50 purpose I have shown in Figs. 9, 10 and 11 a coupling means. It comprises a bolt S having a head at one end and a knurled nut S^1 at the other. Upon the bolt S are two inner sleeves S^2 , S^{21} , each having as shown 55 four eccentric or inclined surfaces s ending in a radial surface which forms a shoulder s^1 . Outside of these sleeves are two other sleeves S^3 , S^{31} each having a spiral cut s^2 so that being made of spring steel they may be 60 opened slightly (see Fig. 10) though normally their edges are in contact. A washer s^3 of substantially the diameter of the tubes B , B^1 separates these sleeves and other washers may be used under the head of the

bolt as shown. Between the inner and outer 65 sleeves are rolls s^{41} which are free to run on the eccentric surfaces s of the sleeves S^2 — S^{21} and are caused so to do by the frictional contact with them of the outer sleeves S^3 — S^{31} and in so doing as they run up the eccentric incline toward the periphery of the inner sleeve they cause the outer sleeve to spread thus increasing its diameter.

To couple a piece of tube B^1 to a piece B which is in the machine the coupling is 70 thrust into the end of the tube B up to the washer s^3 and being of proper size to fit it closely upon giving the coupling a turn in the proper direction the outer sleeve S^{31} engaging the inner surface of the tube is held 75 frictionally while its inner sleeve S^{21} in turning causes the rolls s^{41} to run up the inclines s on sleeve S^{21} and so clamps the coupling to the tube B . The end of another tube B^1 is slipped onto the other end of this 80 coupling up to the central washer s^3 and by turning it carefully the outer sleeve S^3 engages the interior of tube B^1 and being turned with it causes the rolls s^{41} to run up the incline s on the inner sleeve S^2 thus 85 clamping the coupling to tube B^1 . Thus the two tubes are coupled and pass through the machines and are wound as a single length of tube. When the coupling passes out 90 through the winding head, the ribbon is cut 95 at the joint and thereafter the coupling operation is reversed and the tubes are separated, and the coupling removed.

I have described above a simple form of mechanism for accomplishing the desired 100 object, but I do not mean to limit myself to the details herein described. It is obvious to any one skilled in the art that in the motion of winding one thing upon another either the part to be wound or the winding 105 part may be rotated. As shown above the part to be wound is stationary while the winding mechanism rotates. It is also evident that other means of applying power than those described may be used. In fact 110 in various details the elements of the machine may be changed and yet come within the limits of my invention.

As my machine is especially adapted for winding a ribbon on a radiator tube, I have 115 referred to the part B as a tube. So far as the operation of the machine is concerned it should more properly be denominated a core as the machine will perform its operation as well upon a solid rod as upon a tube.

120 What I claim as my invention is:—

1. In a machine of the character described, the combination with means for feeding a core, of a ribbon reel mounted with its axis in parallel relation to said core 125 and adapted to carry a ribbon flatwise, rotating means for feeding said ribbon edgewise to and winding upon said core, said

means comprising a rotary die located about said core and having a spiral guide passage therein comprising several turns for setting, holding and spacing said ribbon, and means 5 for varying the speed of rotation of the ribbon winding means.

2. In a machine of the character described, means for feeding a core lengthwise, a ribbon reel mounted with its axis in 10 parallel relation to said core and adapted to carry a ribbon flatwise, and means for turning said ribbon from a flatwise to an edge-wise position with relation to said core, and means for feeding it edgewise about said 15 core and spacing it thereon, said spacing means surrounding said core and engaging said ribbon for a plurality of turns about said core, whereby said ribbon will be wiped into shape.

20 3. In a machine of the character described, the combination with means for feeding a core longitudinally, of a ribbon reel having its axis concentric with the axis of said core, rotating means for turning said ribbon from a flatwise to an edge-wise position with relation to said core during its 25 passage from said reel to said core, means for winding said ribbon edgewise on said core, said means comprising a spiral die 30 adapted to guide said ribbon to said core and having several turns through which said ribbon passes so that it will be set and held in edge-wise position with relation to said core and spaced along the latter, and 35 means for varying the speed of rotation of the ribbon-winding means.

4. In a machine of the character described, the combination with means for feeding a core longitudinally, of a ribbon 40 reel having its axis concentric with the axis of said core, rotating means for turning said ribbon from a flatwise to an edge-wise position with relation to said core during its 45 passage thereto, means for winding said ribbon edgewise on said core, said means comprising a rotary die having a central opening surrounding said core and having also a spiral ribbon passage, comprising several turns, communicating with said central 50 opening, said die being adapted to guide said ribbon to said core and hold it in edge-wise position with relation thereto and space it along said core, and means for varying the speed of rotation of the ribbon-winding 55 means.

5. In a machine of the character described, the combination with means for feeding a core lengthwise, of a ribbon reel arranged 60 concentric with said core and adapted to carry a ribbon flatwise in parallel relation to said core, rotating means for feeding said ribbon from said reel and winding it edgewise on said core, said means comprising a winding form and means whereby

said ribbon is engaged upon its two flat 65 faces and its outer edge during the process of winding, and means for varying the speed of rotation of the ribbon-winding means.

6. In a machine of the character described, the combination with means for 70 feeding a core lengthwise, of a ribbon reel arranged concentric with said core and adapted to carry a ribbon flatwise in parallel relation to said core, rotating means for feeding said ribbon from said reel and 75 winding it edgewise on said core, said means comprising a winding form and means whereby said ribbon is engaged upon its two flat faces and its outer edge, said winding form being adapted to guide said ribbon, 80 for a plurality of turns during the process of winding, and connected means for varying the feed of said core and the speed of rotation of ribbon winding means.

7. In a machine of the character described, in combination means for feeding a core lengthwise, of a ribbon reel arranged concentric with said core and adapted to carry a ribbon flatwise in parallel relation to the axis of the core, ribbon-winding 90 means comprising a rotating holder having a guideway for said ribbon, a rotating winding form concentric with said core and provided with a spiral passage adapted to receive several turns of said ribbon and wind 95 it edgewise on said core, means for rotating said holder and said winding form, and connected means for varying the feed of said core and the speed of rotation of ribbon-winding means.

8. In a machine of the character described, means for feeding a core and ribbon-winding means comprising a holder having a guideway for said ribbon, a winding form concentric with said core and having a spiral 105 passage, said spiral passage registering with said guideway and a guidestrip forming one side of said guideway and extending into said passage and adapted to coöperate with said core to hold said ribbon as it engages said tube in a predetermined position.

9. In a machine of the character described, a rotating head comprising a reel to receive a coil of flat ribbon, a guide roll on 115 said head adapted to give a partial turn to said ribbon, the axis of said roll being at an angle to the axis of said reel, in combination with a rotary winding device attached to said head and provided with an opening 120 therethrough for a core, means for feeding said core, means for rotating said head, and connected means for varying the feed of said core and the speed of rotation of said winding device.

10. In a machine of the character described, a ribbon-winding mechanism comprising a holder and a winding form hav-

ing a spiral passage therein and an opening therethrough, said winding form being adjustable in said holder lengthwise the axis thereof and said holder being provided 5 with means whereby said winding form may be clamped therein.

11. In a machine of the character described, a rotating head comprising a reel to receive a coil of flat ribbon, a guide roll 10 on said reel adapted to give a partial turn to said ribbon, the axis of said roll being at an angle to the axis of said reel in combination with a winding mechanism attached to said reel and provided with an opening 15 therethrough for a core and means for feeding said core and means for rotating said reel.

12. In a machine of the character described, a ribbon-winding mechanism comprising a holder and a winding form having 20 a spiral passage therein for a plurality of turns the walls of said passage being adapted to yield axially and means for holding said passage open as set forth.

25 13. In a machine of the kind described, in combination with a ribbon-winding mechanism, a core feeding mechanism comprising two positively-driven rolls adapted to bear on the sides of the core and means for 30 rotating them, and means for supporting the under surface of said core.

35 14. In a machine of the kind described, in combination with a ribbon-winding mechanism, a core-feeding mechanism comprising two positively-driven rolls adapted to bear on the sides of the core and means for 40 rotating them, and an idler roll located to support the under surface of the core.

45 15. In a machine of the character described, in combination with a ribbon-winding mechanism, a core-feeding mechanism comprising pivoted brackets, shafts located therein, means for rotating said shafts located at the pivoted end of said brack-

ets and friction rolls located at the swing- 45 ing ends of said shafts and means for causing the free ends of said brackets to approach and for holding them in proximity whereby said friction rolls will engage 50 said core.

16. In a machine of the character described, a ribbon-winding mechanism and means for rotating it, comprising a sleeve, 55 a reel and a winding form carried thereby, said reel being mounted on said sleeve, said sleeve carrying a cam, a friction disk also mounted on said sleeve free to turn thereon, said friction disk also carrying a cam to engage the cam on said sleeve whereby said friction disk may move said sleeve and a 60 friction roll engaging said friction disk, and means for rotating said friction roll.

17. In a machine of the character described, a ribbon-winding mechanism and means for rotating it, comprising a sleeve, 65 a reel and a winding form carried thereby, said reel being mounted on said sleeve, said sleeve carrying a cam, a friction disk also mounted on said sleeve free to turn thereon, said friction disk also carrying a cam to engage the cam on said sleeve whereby it may move said sleeve, and means for rotating 70 said friction disk comprising a second friction disk having an axis parallel with said sleeve and recessed at its center, a shaft having a friction roll at each end, each engaging one of said friction disks, said shaft being supported radially to both friction disks, and means for moving said shaft lengthwise whereby said friction rolls will be moved 75 with relation to the centers of said friction disks to adjust the speed of said first-named disk or to stop it, as described.
